(57) **CLAIM**

The ornamental design for an outdoor condensing unit, as shown and described.

DESCRIPTION

FIG. 1 is a perspective view of the condensing unit of the present invention;

FIG. 2 is a top view of the condensing unit of the present invention;

FIG. 3 is a front elevational view of the condensing unit of the present invention;

FIG. 4 is a bottom view of the condensing unit of the present invention;

FIG. 5 is a rear elevational view of the condensing unit of the present invention;

FIG. 6 is a side elevational view of one side of the condensing unit of the present invention; and,

FIG. 7 is a side elevational view of the opposite side of the condensing unit of the present invention.
